UNITED STATES PATENT OFFICE.

JOSEPH O. LANGGUTH, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTER.

1,313,092.

Specification of Letters Patent. Patented Aug. 12, 1919.

Application filed July 12, 1917. Serial No. 180,070.

To all whom it may concern:

Be it known that I, JOSEPH O. LANGGUTH, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters and particularly to devices for positively locking the movable members of knife-blade switches in the open and closed positions thereof.

One object of my invention is to provide a latching device that shall be positive and simple in construction and applicable to knife-blade switches of existing types without any considerable alteration in the structures thereof.

Figure 1 of the accompanying drawings is a side elevational view of a knife-blade switch embodying my invention; Fig. 2 is a detail view, partially in elevation and partially in section, of the same, and Fig. 3 is a sectional view taken along the line III-III of Fig. 2.

Referring to the drawings, a knife-blade member 1 is pivoted on a pin 2 that is mounted in a terminal support 3 which is secured to a base 4. The member 1 is adapted to be moved, in the usual manner, into and out of engagement with contact members 5 and 6 that are also secured to the base 4.

The terminal support 3 comprises a body portion 7 and jaw portions 8 which embrace one end of the knife-blade member 1. A sliding member 9 is disposed within the jaws 8 intermediate the blade 1 and the body portion 7.

The member 9 is provided with an insulating handle 10 by which it may be moved within the limits imposed by a pin-and-slot connection 11. A spring 12 is disposed in a recess 16 in the member 9 and effects frictional engagement between the members 8 and 9 to hold the member 9 in any position to which it may be moved. The member 9 is provided with an arcuate edge 13 and shoulders 14 and 15 that are adapted to permit rotative movement of the blade member 1 when in certain positions relative to it and

to prevent such movement when in certain other positions.

When the member 9 is in the position shown in Fig. 1, the blade member 1 cannot be disengaged from the contact member 5, by reason of its engagement with the shoulders 14 and 15 of the member 9. In order to open the switch, the attendant must first move the member 9 toward the contact member 6 for the purpose of disengaging the member 1 from the shoulder 15, after which the member 1 may be securely locked either in its mid position or in its position in engagement with the contact member 6 by moving the member 9 back to substantially the position shown in Fig. 1.

When the member 1 is in full engagement with either of the stationary contact members or is in its mid position, the locking may be effected in the manner indicated in Fig. 1. Shifting of the member 9 to the one or the other of its limiting positions on either side of the central or locking position, as shown in Fig. 1, brings the arcuate edge 13 to such position as to permit the free rotation of the pivot end of the blade member.

It is obvious that many changes may be made in the structure which I have described and shown without departing from the intent and spirit of my invention which is to be limited only by the scope of the appended claims.

I claim as my invention:

1. A lock and support for electrical switches having one or more blades hinged at one end between suitable jaws, comprising an adjustable plate located between said hinge-jaws and having projecting portions that are adapted to be engaged by the end of a switch-blade when the plate is in its mid position, one of said projections being removed from such relation when the plate is in one of its extreme positions.

2. A double-throw, knife-blade switch having a sliding plate mounted between its hinge-jaws behind the blade and provided with projecting edge portions that are adapted to be engaged by the blade when the plate is in its mid position and is out of the path of movement of the blade when the plate is in one of its extreme positions.

3. A double-throw, knife-blade switch

provided with a sliding plate having means for adjusting it to lock the switch-blade in each of its full closed positions and the open position and for moving it out of such locking relation.

4. A circuit interrupter comprising two stationary contact members, a terminal member, a double-throw knife-blade member pivoted at one end on the terminal member and a slidable member formed to coöperate with the pivot end of the knife-blade

member and the terminal member to permit free movement of the knife-blade member between the neutral position and each of the closed positions and to preclude movement thereof in both of the closed and neutral positions. 15

In testimony whereof, I have hereunto subscribed my name this 30th day of June, 1917.

JOSEPH O. LANGGUTH.
